MARINE LAMP

Louis E. Perkins, Brooklyn, N. Y.

Application December 31, 1931
Serial No. 584,125

1 Claim. (Cl. 240—7.5)

This invention pertains to marine lamps. More particularly it pertains to an improved means for illuminating marine lamps. It is an object to provide a marine lamp of simple and practical construction in which the source of illumination is readily accessible in a novel and convenient manner. Further objects and the advantages of the inventive idea will be apparent from the following specification. This application is a continuation in part of my application Ser. No. 334,679, entitled Combination marine lamps, filed January 24th, 1929, and pertains more particularly to the improved construction illustrated in Figure 6, of the drawing and fully described in the original specification.

Referring to the accompanying drawing:

Fig. 1 is a side elevation of a marine lamp representing one embodiment of my invention. Fig. 2 is a side elevation of same, in section, showing the illuminating means in position. Fig. 3 is a detail of the novel method of removably retaining the illuminating means.

The lamp housing 6, it will be understood, may be of any suitable type and construction employed in the manufacture of marine lamps. A hollow, cast body of cylindrical form is shown, by way of example. Fitted in an opening in the body is a suitable lens 7. The flange 8, serves as a base for the lamp by means of which it may be secured to the boat. The member 9, represents a suitable means for retaining the illuminating means in place in the body. The means 9, may be a threaded plug as shown or any other suitable retaining means may be employed. Referring to Fig. 2, the threaded plug 9, is shown in place, in a tapped boss formed in a part of the body shell, which may be located where ever desired. Passing thru the opening 11, in the boss is a suitable electric lamp socket 12, provided with a base 13, and carrying an electric bulb 14. The plug 9, engages the base 13, thereby retaining the illuminating member in place, as shown. The opening 11, is sufficiently large to permit the withdrawal of the complete lamp socket and electric bulb for replacing when required, from outside the lamp body.

Electricity is supplied to the lamp bulb by a flexible wire or cable 15, of such length as to permit removal of the lamp. Fig. 3, (Fig. 6 of the original application) is an enlarged detail view in which 6a, is a part of the lamp body shell carrying the boss 10. The socket base 13, is retained against the shoulder 16, by the retaining means 9, which may be of any suitable design. To aid in removing the lamp and socket,

the base is provided with a projection or handle 17, and the plug 9, is provided with a screw-slot 18.

Heretofore, marine lamps have been provided with a door in the body of the lamp to afford access to the interior, or if no door is provided, it has been necessary to remove the lamp from the boat to which it is fastened, thus affording access to the interior thru the open bottom. By the means shown, a simple water-tight lamp may be constructed which may be secured in place on the boat, and re-bulbing is easily accomplished in the manner described. Elimination of the door reduces the cost of construction and simplifies the construction. Moisture does not seep in and interfere with the electrical connections. If desired, a gasket may be inserted between the shoulder 16, and the base 13. An important feature of this inventive idea is that it permits a wide range of body designs, stream-line effects and special shapes because of the absence of the usual door and the use instead thereof of the small and unique lamp retaining means shown and described. In the original application, it will be noted that the lamp socket is carried by the means which is employed for securing it in place in the lamp body and that a swivel joint, for example, is employed to prevent twisting the electric supply wires when the retaining means is rotated while being secured in place. In the present invention there is no tendency to twist the wires because the lamp socket is independent of the securing means as shown.

I claim:

In combination, a marine lamp, a boss formed on its inner wall, an aperture formed thru said boss, a shoulder formed within said aperture at the inner face of said boss, an electric lamp socket projecting inwardly thru said aperture and into the interior of the marine lamp, a base plate carried by said socket and engaged by the shoulder within the aperture, a threaded plug screwed into the aperture for retaining the base plate in engagement with said shoulder, and means within the lamp body for supplying electric current to the lamp socket comprising a flexible electric cable of sufficient length to permit the removal of the socket outwardly thru said aperture.

LOUIS E. PERKINS.
